UNITED STATES PATENT OFFICE.

AUGUSTUS M. ROSSI, OF BARRE, VERMONT.

STONE-SAWING MACHINE.

1,242,983.

Specification of Letters Patent. Patented Oct. 16, 1917.

Application filed March 21, 1917. Serial No. 156,348.

To all whom it may concern:

Be it known that I, AUGUSTUS M. ROSSI, a citizen of the United States, residing at Barre, in the county of Washington and 5 State of Vermont, have invented certain new and useful Improvements in Stone-Sawing Machines, of which the following is a specification.

This invention relates to stone sawing machines, and more specifically to a machine adapted to handle relatively large blocks of stone and conveniently saw and cut them into smaller pieces.

One of the objects of the present invention is to provide a simple and practical stone sawing machine of the above general character which will be reliable and efficient in use and operation. A further object is to provide a machine of the above character 20 which will be substantially automatic in its operation. A further object is to provide a strong and durable apparatus of the above character which will be relatively inexpensive to construct and install.

25 Other objects will be in part obvious from the annexed drawings and in part indicated in connection therewith by the following analysis of this invention.

This invention accordingly consists in the 30 features of construction, combination of parts and in the unique relations of the members and in the relative proportioning and disposition thereof, all as more completely outlined herein.

35 To enable others skilled in the art so fully to comprehend the underlying features thereof that they may embody the same by the numerous modifications in structure and relation contemplated by this invention, 40 drawings depicting a preferred form have been annexed as a part of this disclosure, and in such drawings, like characters of reference denote corresponding parts throughout all the views, in which—

45 Figure 1 is a plan view of the complete apparatus;

Fig. 2 is an end elevation view, partly in section, of the complete apparatus;

Fig. 3 is a detail view showing the carriage feed mechanism;

Fig. 4 is a detail fragmentary view showing a portion of the saw blade;

Fig. 5 is a detail fragmentary elevational view showing a part of the carriage feed.

55 In order that a clearer perception of the present invention may be had it may be

stated that the apparatus is designed primarily for handling relatively large blocks of stone, and comprises a pair of rotatable saw blades mounted in a suitable frame and 60 adapted to operate upon a block of stone carried by two cars positioned at opposite sides of the plane in which the saw blades lie, the cars being automatically fed as the saw blades revolve. 65

Referring now to the drawings in detail, and more particularly to Fig. 1, 10 denotes four vertical uprights connected by two transverse members 11 and 12, and two longitudinal members 13 and 14. The parts 70 are suitably braced and connected to provide a rigid and substantial structure adapted to carry the saw blades and the motive means for driving the blades, as well as the automatic carriage feed. 75

Below the framework, which may be considered a hollow trestle, are two tracks 15 and 16 adapted to support independent cars 17 and 18 upon which a block of stone 20 is adapted to rest. As indicated in Fig. 2, 80 these cars are slightly spaced apart, and lying in a vertical plane therebetween are two rotatable saw blades 21 and 22, mounted upon suitable shafts 23 and 24, respectively, the lower one of which dips into the usual 85 shot and water pit 19 as indicated.

These saw blades are mounted in the same vertical plane but their centers are slightly offset, so that the lower edge of the blade 22 projects below a horizontally disposed tangential line to the blade 21, thus insuring a complete cutting of the stone as it is passed thereby. In order to obtain this staggered relation of the saw blades the shaft 23 is mounted upon one side of the transverse 90 member 11 while the other shaft, 24, is mounted upon the opposite side, as shown clearly in Fig. 1. Both of these shafts are provided at their ends with beveled gears 25, meshing with similarly shaped gears 26. 95 One of these gears 26 is carried by a stub shaft 27 while the other is carried by a vertically disposed shaft 28 at the opposite side of the upright 10. Interposed between the gears 26 is an idler shaft 30 provided 100 with a pinion 31 meshing with suitable pinions 32 on the stub shaft 27, and main shaft 28, thus to obtain the desired rotation of the saw blades. 105

It will be noted by reference to Fig. 2, 110 that the upper shaft 24 with its respective saw blade is mounted in suitable adjustable

bearings 35, which may be moved up and down according to the size of the stone to be sawed, and if desired it may be lowered sufficiently to project below the plane of the car 17 and 18, and dispense with the lower saw 21. The shaft 28 is provided with a splined connection with the bevel gear 26, in order that this latter may be moved to accommodate itself to the adjustment. In order to obtain a uniform adjustment at both ends of the shaft 24 a transverse shaft 36 is provided with pinions 37 meshing with pinions 38, carried by vertical shafts 40 connected with the bearings 35. This shaft 36 may be rotated in any desired manner through the medium of wheel 41 at its end.

In order to obtain the desired feed of the cars 17 and 18 with respect to the rotation of the saws, each car is provided with a rack member 45 projecting downwardly from one side thereof, as shown in Fig. 5. These rack members mesh with suitable pinions 46 mounted upon transverse shafts 47, as shown in Fig. 1. Each shaft is of course mounted in suitable fixed bearings 48 and is provided at its end with the bevel gears 50 meshing with a second bevel gear 51 on shaft 52, provided intermediate its ends with a worm 53 meshing with gear 54, carried by a vertical shaft 55, the opposite end of which shaft is provided with suitable bevel gearing 56 connecting with a transverse shaft 57 extending across the top of the frame work. Fast and loose pulleys 58 are mounted upon this shaft and connected by means of a belt 60 with a motor 61 seated at the top of the framework. A suitable belt-shift 62 is provided as well as a clutch member 63, upon the shaft 57. This clutch member is interposed between the driving means and pawl and ratchet mechanism 64, as shown more clearly in Fig. 3, which is connected by means of an eccentric drive 65 with the driven shaft 70. This construction permits the cars to be moved rapidly from one end of the track to the other by releasing the clutch 63 and connecting the fast pulley with the motor 61, in order to obtain the initial positioning of the stone with respect to the saw blades. After this initial positioning or removal of the cut stone, if the case be such, the belt is shifted to the loose pulley, the clutch 63 connected, and thereafter the cars are automatically driven through the mechanism shown in Fig. 3, to feed the stone progressively as the saws rotate.

Any suitable form of power may be used for driving the several parts but it is believed that a motor 66 mounted upon the framework, as shown in Fig. 1, and connected by means of a belt 67 with a driven pulley 68 upon a shaft 70 mounted at the top of the frame is preferable. This shaft 70 carries a bevel gear 71 meshing with a bevel gear 72 upon the shaft 28. The motor con-

trol for both motors 61 and 66 may be located at any convenient spot.

While the saw blades may be of any desired construction suitable for sawing stone, there is indicated in Fig. 4 a preferred embodiment in which the blade proper 75 is provided with notches 76 uniformly arranged about its periphery, in which are mounted tooth members 77, each carrying two teeth 78, connected with the body of the saw by means of rivets or other suitable form of holding means 80.

The operation and method of use of a device of this character is substantially as follows:

The block or slab of stone 20 to be cut is positioned upon the cars 17 and 18, and with the clutch 63 disconnected, the motor 61 is started which will move the cars through the medium of the rack and pinion, as shown in Fig. 5, into position closely adjacent the saws. The belt 60 is then shifted and the motor stopped and clutch 63 connected. The motor 66 is then started which drives the main shaft 70, and through the various bevel gearing and transmission shafts both saws 21 and 22 will be rotated in the desired direction. As soon, however, as the saws start to rotate the pawl and ratchet mechanism illustrated in Fig. 3 will come into operation to feed cars 17 and 18 forwardly, so that the stone is actually engaged by the saw blades and is progressively fed as the blades cut into the stone. The peculiar relation and position of the saw blades permit a clean even cut of the stone straddling the two cars 17 and 18. After the block has been cut through the driving motor 66 is stopped and the feed motor 61 started, after properly positioning the belt upon the fast pulley and releasing the clutch 63, to remove the cars 17, 18, backwardly or forwardly, as desired.

It is thus seen that the present invention provides a simple and practical apparatus of the above general character adapted to accomplish, among others, all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claim.

Having thus described my invention what I claim as new and desire to secure by Letters Patent is:

In a stone sawing apparatus, in combination, an inverted U-shaped framework, a saw

adapted to revolve in a vertical plane between the legs, a pair of cars adapted to travel upon tracks on the opposite sides of the saw, a shaft at the top of said framework, two sources of power associated with the framework and adapted to be connected with said shaft means connecting said shaft and saw whereby they rotate together, means connecting said shaft with the cars for moving the cars with respect to the saw and clutch mechanism for operatively connecting

one source of power with said shaft for rotating the saw and feeding the car proportionally or to connect with the other source of power to rapidly position the car with respect to the saw without rotating the saw. 15

In testimony whereof I affix my signature in presence of two witnesses.

AUGUSTUS M. ROSSI.

Witnesses:

S. HOLLISTER JACKSON,
EDNA G. JENNINGS.
